APPARATUS FOR CONDITIONING THE SURFACES OF METAL BODIES

James H. Bucknam, Cranford, Alfred J. Miller, Garwood, and Arthur M. Keller, Livingston, N. J., assignors to The Linde Air Products Company, a corporation of Ohio

Application February 9, 1939, Serial No. 255,398

24 Claims. (Cl. 266—23)

This invention relates to apparatus for conditioning the surfaces of metal bodies, by applying high temperature localized heat on a zone extending completely across a wide surface of such body and relatively moving the body and the heat applying means to progressively condition the entire surface. The invention relates more particularly to an apparatus for thermo-chemically removing a layer of metal from an upper surface or from an upper surface and a side surface of a semi-finished steel shape such as a billet, bloom or slab, and for eliminating scale from such surfaces.

In the casting of steel ingots and during the hot rolling of steel, defects such as scale, surface cracks, slag inclusions, seams, and the like, appear on and in the surfaces of the steel being processed, and in order to reduce the number of rejections of finished products made from the resulting steel shapes, the surface defects are generally removed before or during an intermediate stage of the rolling. Scale is commonly removed by pickling and other defects have been eliminated by chipping away the defective surface metal. Hand-operated blowpipes having suitable nozzles are now also used for thermo-chemically removing the defective surface metal adjacent each defect by effecting a combustion of the steel with oxygen. Lately, machines employing suitable nozzles have come into use for simultaneously conditioning the entire side surfaces of rectangular billets and for simultaneously conditioning the two opposite side faces of such billets when the billets are cold and also while they are at a rolling temperature and are passing from one rolling operation to another.

The present invention provides a machine for thermally conditioning the top surface of a steel shape such as a billet, bloom or slab, for eliminating scale accretions and more particularly, for thermo-chemically removing a layer of surface metal from the entire top surface or from the top surface and an edge surface of a steel bloom or slab while it is passing from one rolling operation to the next. A blowpipe head producing high temperature heating flames and/or an oxygen stream of relatively great width sufficient to extend substantially across the top surface of a slab is supported above the slab in such a way that the head is movable in a plane transverse to the slab supported on a roll table. The blowpipe head is moved relatively along the surface of the slab from one end edge thereof to the opposite edge. When surface metal is removed, the head is maintained in contact with the work sur-

face during the movement in order that the surface metal may be uniformly removed and the gas efficiently used. The supporting mechanism is so arranged and constructed that the head is maintained parallel to or in contact with the slab surface irrespective of changes in the level of the surface and irrespective of the warp or twist of the slab. The head may be quickly lowered and raised from the operating position adjacent the work and the entire machine may be moved laterally away from the conveyor line when it is desired to pass slabs along without a surfacing treatment. When an edge surface is to be simultaneously conditioned an auxiliary blowpipe head is provided at one end of the main head and the supporting mechanism is arranged to provide a lateral floating movement of the heads to maintain the auxiliary head also in the operating position with respect to the edge of the slab.

The principal objects of this invention are to provide apparatus for surface conditioning an entire face or two adjoining faces of a ferrous metal body such as a slab or bloom; to provide apparatus for removing a layer of surface metal particularly while such body is at rolling temperature and in transit from one rolling operation to the next; to provide such an apparatus which may be installed to operate in conjunction with an existing conveyor table of a steel mill; to provide a relatively wide gas-delivering device which shall surface condition the entire width of a slab in a single pass; to provide mechanism for moving the gas delivering device into engagement with the surface or surfaces being treated and for maintaining such gas delivering device in uniform relation to the surfaces across the entire width of the surfaces during the operation irrespective of variations in the level of the surfaces or a warp or twist of the body; and to provide such apparatus for simultaneously surface conditioning the top surface and an adjoining edge surface of a steel slab.

These and other objects and novel features of this invention will become apparent from the following description taken in connection with the accompanying drawings in which:

Fig. 1 is a perspective view of an exemplary apparatus in position over a slab for thermally or thermo-chemically treating the top surface of the slab according to the invention;

Fig. 2 is an elevational view of the apparatus shown in Fig. 1 with parts broken away to show the counterbalancing mechanism;

Fig. 3 is a plan view of the mechanism shown in Figs. 1, and 2;

Referring to Fig. 1, the steel body to be surface-treated may, for example, be a slab shown at S which is supported upon the power-driven rollers 20 of the customary steel mill conveyor table C. The conveyor rolls 20 are supported in bearings in a frame and are connected by gearing 35 to the conveyor table driving motor in the customary manner. The blowpipe head for projecting gases against the top surface of the slab S is shown generally at H. The head H extends transversely across the slab and has a width sufficient to cover the widest slab to be surface-treated. The head H is supported preferably at each end thereof by lifting devices or jacks which are enclosed within two columns J adjacent each end of the head and depending downwardly from the frame or carriage F between the overhead ways or rails upon which the carriage F runs. The rails R may be supported in any suitable manner, as upon parallel beams 21 which are horizontal and extend transversely of and above the conveyor line or roll table C. The ends of the beams 21 may be supported in any suitable manner, as by the supporting columns or walls of a building or by special supporting frames. Also, depending from one end 55 of the carriage F and between the rails R is another column-like housing shown generally at W for enclosing the weights which counterbalance the blowpipe head H.

Referring to Figs. 1, 2, and 3, the carriage or frame F comprises a pair of long side plates 22, parallel and spaced apart by several cross members rigidly secured thereto, preferably by welding. Such cross members include the pair of vertical plates 23 at the left portion of the carriage and similar plates 24 near the right-hand end of the carriage. The plates 23 are spaced apart approximately the same distance as the side plates 22 are spaced, and they depend downwardly below the carriage F to form the inside and outside walls of the left-hand jack column J. The pair of plates 24 similarly form the inside and outside walls of the right-hand column J. Four wheels 25 are employed for supporting the carriage upon the rails R. The wheels 25 are disposed outside of the plates 22 and are mount-

ed at the ends of axles 26 which pass transversely through the plates 22 and through bearings 27, secured to the outside surfaces of the plates. One axle 25 is disposed between the plates 23 and the other is disposed between the plates 24. Only the left-hand axle is power-driven although both axles may be driven if desired. For moving the carriage transversely of the roll table and along the rails R, a worm-gear 28 secured to the mid-portion of the left hand axle 26 is provided. The worm-gear 28 meshes with a worm 29 disposed above the axle 26 and mounted on a shaft 30 that is journalled at its left end in a bearing 31 secured to the left plate 23. The other end of the shaft 30 passes through the right-hand plate 23 and a bearing 32 mounted thereon to a speed-reducer 33 which is directly coupled with an electric motor 34. The reducer 33 with motor 34 is supported upon a horizontal plate 35 secured to the side plates 22. For safety reasons and to prevent dirt from settling on the rails R, the wheels 25 are covered by hoods 36 secured to the outside of each side plate 22. The lower portions of plates 23 that form the inside and outside walls of the left jack housing column J are joined by side plates 37 which have their upper ends also welded to the lower edges of the side plates 22. Side plates 38 similarly form with plates 24 the right-hand jack column J.

The weight-housing W comprises a box formed by four vertical plates two of which are side plates 39 secured against the inside surfaces of side plates 22 and near the right-hand end thereof. The other two plates 40 are inside and outside wall plates secured between the plates 39. The weight-housing W is also provided with a bottom 41 firmly secured to the plates 39 and 40. For counterbalancing the major portion of the weight of the head H, two counterweights 42 are employed, although if desired, a single counterweight may be used. The weights 42 move vertically within the housing W and are suspended therein by chains 43 which pass over pulleys 44 in the upper portion of the housing W. From the pulleys 44 the chains 43 pass horizontally between plates 22 to two pulleys 45 directly above the head H and spaced apart an equal distance from each side of a vertical center line through the head H. From the pulleys 45 which are secured to cross-brackets 46 secured between side plates 22, the chains depend vertically downward and are connected to the head H.

The head H is moved vertically preferably by motor operated mechanism. To this end, adjacent the left-hand end of the carriage frame F is mounted a motor 47 on a horizontal bracket plate 48 between the side plates 22. The shaft of the motor 47 carries a sprocket 49 which is connected by a chain to drive a sprocket 50 mounted on and adjacent the left-hand end of a horizontal jack shaft 51. The Jack shaft 51 is disposed below the side plates 22 and passes through both jack columns J, being journalled in bearings 52 secured to the outside faces of the plates 23 and the plates 24. The jack shaft 51 is positioned back of the center line of the carriage so as not to interfere with the chains 43. The motor 47 is preferably provided with a magnetic brake 53 so that it can be accurately stopped and locked in the stopping position. To control the vertical movement of the heads H, a limit switch mechanism is preferably provided and disposed underneath the motor 47. The limit-switch mechanism may comprise a spur-gear 55

mounted on the end of the jack-shaft 51 which gear meshes with a spur-gear 56 on the end of a shaft 57 extending from the limit-switch housing 58, secured to the under side of the plate 48. The lifting-jack mechanism is shown in detail in Figs. 5 and 6. Only the left-hand jack is described because the right-hand jack mechanism is similar but opposite handed. This mechanism comprises a vertical screw 59 which has its lower end journalled in a footstep bearing 60 supported on the bottom 61 of the jack column. At the upper end of the screw 59 is mounted a worn-wheel 62 which meshes with a worn 63 on the jack shaft 51. The upper journal of the screw 59 is journaled in a roller bearing 64 that is mounted on a bracket plate 65 secured between the side plates 37, the screw 59 being suspended vertically by the bearing 64. The turning of the screw 59 moves vertically the special nut 66 which is in threaded engagement thereon. In Fig. 6 it will be seen that the nut 66 is provided with two projecting ears 67 which engage the under surface of a plate 68. The plate 68 is secured to the top end of a box-like portion 69 of the blowpipe head supporting bracket 70. The box portion 69 surrounds the nut 66, a considerable clearance space being provided between the nut 66 and the inner walls of the box 69 which are also provided with vertical channels 71 into which the ears 67 project in order that the nuts 66 will be prevented from turning with the screw 59. The plate 68 has a hole through it having a diameter larger than the nut 66 so that only the ears 67 can contact with the plate. This construction provides a loose engagement of the bracket box 69 with the nut 66 so that the bracket 69 can rock laterally with respect to the nut. If it is in the lowermost position, the open bottom of the box 69 rests in contact with four springs 72 secured to the bottom plate 61 of the column.

Means is provided for guiding the vertical movement of the box 69 within the column J. Such means should maintain the box 69 substantially vertical while permitting it to rock laterally in the plane of the section of Fig. 5 and while preventing fore and aft displacement or excessive transverse displacement of the head H. To this end, in the present example, a set of four rollers guided by vertical guide channels are provided. One pair of the rollers 74 is guided between vertical, spaced-apart angle irons 73. One leg of each angle 73 is secured to the inside surface of the left-hand plate 23 and the other legs are spaced apart and parallel to form a guide channel for the rollers 74 which are journalled on two trunnions 75 projecting horizontally leftward from the box 69 and respectively located adjacent the upper and lower ends thereof. A second pair of rollers 76 is provided and mounted on the end portions of a trunnion shaft 77, the axis of which is in perpendicular relation to the trunnions 75 and located substantially midway between the trunnions 75 and adjacent the left-side wall of the box 69, the rollers 76 being located outside the box 69 and adjacent the front and back walls thereof. The rollers 76 are guided vertically by guide-bars 78 and 79 secured against the inside walls of the front and rear plates 37 of the column J. The guide channel between parallel bars 78 and 79 is made wider than the diameter of the rollers 76 in order to permit a desired degree of freedom of movement. Brackets 70, for supporting the blowpipe head H, project from the right-hand wall of the box 69 through an opening 80 in the right-hand plate 23 of the column J. The opening 80

is vertically long enough to permit movement of the bracket 70 through its full range and, to keep out dust and dirt, the portion of the opening not occupied by the bracket 70 may be enclosed by suitable means such as cover plates 81 having 5 their side edges retained in vertical channels 82 so that the plates may slide vertically with the bracket. The blowpipe head H is connected to the brackets 70 by means of the water-cooled front plate 83 whose ends are each secured to the 10 end of each bracket 70, preferably by bolts 84.

As best shown in Figs. 1 and 7, the front plate 83 comprises a rectangular plate having its length dimension horizontal and transverse to the slab and its width dimension vertical. As previously 15 described, the plate 83 is supported at each end by the corresponding jack brackets 70. To effectively cool the plate and overcome the heat radiated from the surface of the work and from the desurfacing reaction, the plate 83 is provided 20 with a chamber 85 for cooling water which is introduced into the chamber near the upper right-hand corner of the plate through pipe 86 and discharges from the upper-left corner of the plate through a pipe 87. 25

The blowpipe devices of the head H are more clearly shown in Figs. 4 and 7. They are secured to the front plate 83 by a row of support or frame plates 88 which are secured against the back of the front plate by means of bolts 89. Each frame plate 88 carries an individual nozzle header 90, of which one or more may be employed to make up the desired width of blowpipe head H. Nozzle headers similar to the type here employed are shown and described in detail in the copending 30 application, Serial No. 174,335, filed November 13, 1937, by James H. Bucknam, and entitled: Blowpipe apparatus. In the apparatus herein described, a plurality of headers 90 are employed, each having eight nozzles 91. Each nozzle 91 35 produces a central jet of low velocity oxygen surrounded by preheating flames. The headers 90 contain suitable passages for supplying the heating gas mixture and the cutting oxygen separately to each nozzle. The nozzles 91 project downwardly and forwardly from each header 90 and are clamped or disposed in a transverse row, the oxygen orifices of the row of nozzles being spaced at such intervals that the gas streams projected thereby merge on the surface of the slab to provide in effect a sheet-like desurfacing stream. However, for thermal surface treatments other than thermo-chemical surface removal, it may be desirable that the gas streams shall not be close enough to merge. For example, when removing 40 scale it is preferable that spaced-apart heating flames be projected from the header nozzle orifices and preferably directed substantially perpendicular against the plate surface. 45

Each header 90 is secured to its corresponding 50 frame-plate 88 by a pair of ears 92 projecting upwardly from the forward face of the header. Each header 90 is supplied with heating gas mixture by four vertical gas mixers or blowpipes 93 which discharge into the header and 55 are secured at their upper ends to a bracket 94 projecting from the rear of each plate 88. The cutting oxygen is supplied to each header 90 by vertical pipes 95 connecting the header to a transverse oxygen manifold 96. The manifold 60 96 is supplied with oxygen through a hose 97 which connects to the discharge side of a solenoid-operated control valve 98. Several such control valves 98 are connected to another transverse oxygen supply manifold 99 supported upon a 65 70 75 76 77 78 79 80 81 82 83 84 85 86 87 88 89 90 91 92 93 94 95 96 97 98 99 100

transverse platform 100 secured at each end to the columns J. The main oxygen supply to the manifold 88 is through a conduit 101. The oxygen and the acetylene which are the gases preferably employed for forming the pre-heating gas mixture are supplied to the blowpipe 93 by short manifolds 102 and 103 which receive oxygen and acetylene from flexible conduits 104 and 105. Each blowpipe 93 is connected to the oxygen manifold 102 by a tube 106 and each blowpipe is connected to the acetylene manifold 103 by a tube 107. Suitable control valves 108 and 109 for each tube are provided and are set to deliver the gases in the correct proportion. The manifolds 102 and 103 are supported by a gooseneck bracket 110 secured to the upper edge of the frame plate 88.

The nozzles 91 and blowpipe headers 90 are protected by a wide shoe 111 having a front wall 112, the upper edge of which is secured to the lower edge of the front plate 88. The bottom wall 113 of this shoe is adapted to ride on the surface of the slab S and is preferably provided with a layer of hard surface metal to protect it from excessive wear. If desired, however, rollers 134 hereinafter described, may also be attached to the head H for supporting it on the slab surface in order to reduce friction during operation. The nozzles 91 project through openings at the joint between the front wall and the bottom 113 of the shoe. The back wall 114 of the shoe is secured to the bottom flange of a cross-channel 115 which has its ends firmly secured to the front plate 88 by means of web or bracket plates 116 at each end. The counter-weight chains 43 are connected to the head H by two bolts 117 secured to the top flange of the cross channel 115. The shoe 111 is also provided with end walls which together with its front and back walls form a chamber which holds cooling water surrounding the nozzles 91 and the lower portion of the header 90. Such cooling water is supplied to the shoe at the left end thereof by the pipe 87 which is connected between the front plate 88 and the left-end wall of the shoe. The excess water discharges from the shoe through a pipe 118 which conducts the water from the other end wall of the shoe and discharges it beyond the right-hand edge of the slab S. Cooling water is also supplied to each blowpipe header 90 by a flexible tube 119 supplying water to a manifold 120 from which a tube 121 conducts the water to the blowpipe nozzle header. The water discharges from the cooling chamber of each nozzle header 90 into the water space of the shoe 111. To deflect heat and slag from the blowpipe mechanism, a dust shield 122 (see Figs. 2 and 7) is provided which is hung at each end on brackets 123 secured to the front plates 37 of the columns J. The shield 122 thus hangs vertically in front of the plate 88.

To limit the movement of the carriage F toward the right, a pair of electric-limit switches 124 and 125 are provided as shown in Fig. 7. The switch 124 is mounted on the underside of the front beam 21 and is provided with an arm 126 which contacts with a cam 127 secured to the front side 38 of the right-hand column J. The cam 127 has a triangular contacting surface with the ridge thereof upward so that the arm 126 may ride over the ridge. The switch 125 is mounted on the top surface of the lower flange of the beam 21 and is provided with an upwardly extending arm 128 which contacts with a cam 129 secured to the front side 39 of the weight-housing W.

75 The gases and water are supplied to the ma-

chine from a stationary supply point by suitable flexible or jointed connections that supply oxygen to conduits 101 and 104, fuel gas such as acetylene to conduit 105, and water to conduits 86 and 119, the connections being arranged to permit the movement of the machine through a desired range of travel. Electrical cables (not shown) similarly connect the motors 34 and 47 and the limit switches 124, 125, and 130, with a stationary control panel. The limit switch 130 provides an additional control for the motor 47 when lowering the head H. The switch 130, as shown in Figs. 2 and 3, is secured on a bracket 131 projecting from the rear-side plate 22 and has a downwardly depending switch arm 132 that engages with a 15 cam projection 133 bolted to the upper chain 43.

In order to reduce friction between the shoe 111 and the surface of the slab, two or more rollers 134 may preferably be secured to the shoe to the rear of the nozzles as shown in detail in Figs. 8 and 9. Each roller is secured to the middle of an axle 135 having end portions journaled in bearings 136 which are carried by a bracket 137. The bracket 137 has two horizontal ears 138, one above each bearing which are bolted to the flange 139 projecting rearwardly from the wall 114 of the shoe 111. The bracket 137 is also provided with a forward cross-connecting member 140 which is secured against the back wall 114 of the shoe. Preferably a roller bracket 137 is secured adjacent each end of the shoe 111 with the axis of each roller 134 parallel to the row of nozzle orifices. The periphery of each roller 134 which contacts the work surface from which metal and/or scale has been removed extends to a level 35 very slightly below the bottom 113 of the shoe so that the portion of the weight of the head H that is not counterbalanced is carried by the rollers 134.

It will be seen that the lifting-jack mechanism 40 supports and guides the head H so that it may freely float in a vertical plane whereby either end of the head may automatically adjust itself to a different level than the opposite end in order that the nozzle orifices may be maintained at a uniform distance above the surface of the slab even though such surface does not lie exactly in a horizontal plane.

The operation of the machine when desurfacing a slab is preferably as follows:

It is assumed that the machine has been moved to the left away from over the conveyor table and that all adjustments have been made. The operator stands at a stationary control table (not shown) so located as to allow him a clear view of the work and may, by actuating electrical remote control mechanism, operate the machine as follows: The slab S is brought into a position with its forward end edge located in alignment with the operating position of the nozzles 91 by operating a positioning switch of the control table to energize the electric motor which drives the roll table. By closing a second switch, the motor 34 is started (its brakes 33 being released) and through worm 30 and wheel 29, turns the left-hand wheels 25 which traverse the carriage along the rails R to the right until the arm 126 makes contact with the cam 127. The raising of the arm 126 closes switch 124 which, through a motor control device, reduces the speed of the motor 34. 70 When the arm 128 engages cam 129, the switch 125 is closed operating another control device which stops the motor and applies the brake 33 to hold the carriage F in a fixed position. This position is determined by the relative positions 75

of the cam 129 and switch 125 and is such that the blowpipe head will be directly over the slab S.

The operator then moves a control handle to a first position which releases the brake 53 and starts the motor 47 which turns the screw 59 in each jack column J through worms 62, wheels 63, and jack shaft 51 which is in chain connection with the motor 47. Turning of the screws 59 causes the nuts 66 to feed down and lower the brackets which they carry. The uniform downward movement of the head H continues until the shoe 111 or a roller 134 touches the surface of the work. The motor 47 is not immediately stopped when this occurs, but continues to rotate for a very short interval to permit the nuts 66 to move down a short distance out of contact with the plate 68 so as to permit the head H to ride freely on the surface of the slab. The weight of the head is largely counterbalanced by the weights 42 so that the pressure of the shoe 111 on the surface of the slab is moderate. The actual rotation of the motor 47 is stopped by the action of the limit-switch within the casing 58. An additional control for the downward movement is provided by the limit-switch 130, the downwardly depending arm 132 of which engages cam 133 on the chain 43.

When the head H rests on the slab with the nozzles 91 very close to the end of the surface entering the machine, the operator turns the control handle to a second position which energizes electrically-operated valves that turn on the pre-heating gas mixture which then issues from the nozzles 91. If the slab S is at a rolling temperature, the gases immediately ignite; if not, they may be ignited by an electric spark or by other means. In a very short interval of time the heating flames will raise the surface metal on which they impinge to an ignition temperature, whereupon the operator moves his controller to a third position which energizes the electrically-operated cutting-oxygen valve 98 to open it. The oxygen issues from the nozzles 91 and immediately combines with the surface metal against which it impinges, converting a portion of such metal into a molten slag which flows forward on the surface. The great heat generated by the reaction also removes some of the surface metal in the molten state mixed with the molten slag. Simultaneously, with the turning on of the cutting oxygen, the roll table motor starter is energized so that the slab is propelled along the roll table toward the head H. This movement is on a regulated control speed which is selected according to the character of surface conditioning desired.

When the slab or bloom has passed under the head H and through the machine, the head will drop off the edge a short distance which will pull the cam 132 into contact with the arm 131 and operate the limit-switch 130. This limit-switch 130 de-energizes the roll table motor control to stop the movement of the slab and also de-energizes the electrically-operated gas valves to turn off the gases. The operator however, can anticipate this action by turning the controller handle to a fourth position immediately when the end of the slab reaches the blowpipe head. The fourth position de-energizes the electrically-operated gas valves and closes them unless they have been de-energized by the action of switch 130. The fourth position also energizes the starter of the motor 47 which then operates the jacks for raising the head H. This upward movement is stopped by the limit-switch in casing 58

which de-energizes motor 47 and applies the brake 53 to hold the head locked in the upward position.

The operator can now move the carriage F' to the left if it is desired to move the desurfacing machine away from the conveyor table 5 C, or the roll table C may be operated to position another slab under the head H for a conditioning treatment. In order to condition the other side of the slab, the latter may be run onto a section of the conveyor table, that is provided with a slab manipulator. A suitable slab manipulator is described in the copending application Serial No. 174,286, filed November 13, 1937, jointly in the names of W. C. Weidner and A. M. Keller, and entitled: Method and apparatus for manipulating slabs and the like. The manipulator turns the slab over, after which it is run backward along the conveyor table until the forward edge of the untreated side is in position under the head H. This side is then conditioned in the 20 manner described.

The machine can be quickly adjusted to condition various widths of blooms or slabs. This is done by shutting off those valves 108, 109, and 95' which supply the gases to any nozzles that are not needed or extend beyond the side edges of the slab. It is preferable that the desurfacing flame or gas streams produced by the head H shall be substantially continuous across its width and only slightly wider than the top surface being treated. This is in order that any fins or other defects at the lateral edges will be removed.

Referring to Figs. 10 to 14, inclusive, an alternative machine for surface conditioning both an edge surface as well as the top surface of a slab is shown. This machine is similar in general principles to that illustrated in Figs. 1 to 9, but is differently arranged structurally. The corresponding parts are similarly numbered but have the prefix 2 added to the number.

Instead of being carried on overhead rails, the carriage F' is mounted on wheels 225 which run on cross rails R' secured to the floor underneath the conveyor line. The columns J' extend vertically upward from the carriage frame F' and have their opposed inner faces provided with vertical slideways 145. Two slideways 145 are provided on each column J' and the jack screws 259 are disposed between them. The jack screws 259 are secured at their lower ends in footstep 50 bearings on the carriage F', and at their upper ends are connected by beveled gearing within gear housings 146 to the transverse jack shaft 251. The jack shaft 251 simultaneously turns both jack screws 259 and is connected to the motor 247 by speed reducing mechanism within a housing 147 mounted on top of the left-hand jack column J. The slide brackets 269 threadedly engage with the screws 259 and are slidingly secured to the ways 145 so that the rotation of the screws 259 will raise or lower the slide brackets 269 simultaneously. Each slide bracket 269 is provided with two arms 148 which extend forwardly and inwardly and are pivotally connected to corner bearings 149 of two horizontally swingable links 150. The links 150 are of the same length and extend rearwardly. The rear corners of links 150 are provided with corner bearings 151 which are pivotally connected to arms 152 that extend forwardly from each end of cross member 153. The cross member 153 is thereby transversely and freely movable horizontally and is urged leftward by suitable means such as, for example, by a spring 154 shown more clearly in Fig. 14. The spring 154 is secured between the right-hand slide 75

bracket 269 and the right-hand link 150 and has its ends supported within a socket 155 in the link 150 and a cup 156 on the bracket 269.

The slab S is supported during its passage 5 through the machine by a roller 220 that has its axle journaled in bearings 157 mounted on the frame F'. The roller 220 is disposed a sufficient distance in front of the head H' in order to avoid interference with the operation thereof. When 10 the carriage F' is moved to the right so that the surface-conditioning mechanism is away from the operating position, the slabs S that are passed along the conveyor line are supported by an auxiliary roll 220' which is mounted in bearings 158 15 on the right-hand portion of the frame F'.

The head H' is supported by the cross member 153 in such a manner that it is freely movable vertically in order that the nozzles 91 may be maintained in constantly uniform relation with 20 the surface irrespective of the local variations in the height of the surface. To this end the transverse shoe 159 is provided at each end thereof with a vertically extending guide 160. The guide 160 is vertically slidable in a channel 25 formed by the legs of two parallel vertical angles 161 which are secured against the end wall 162 of the cross member 153. Endwise motion of the shoe 159 with respect to the cross member 153 is prevented by a single roller 163 on each 30 guide 160 that bears against a track 164 on the end wall 162. The weight of the shoe 159 is counterbalanced by tension springs 165 having lower ends secured to ears 166 projecting inwardly from the front wall of the shoe 159 and their 35 upper ends secured to ears 167 on the cross member 153. The shoe 159 is provided with a front wall 168, a bottom wall 169, and a rear wall 170, the nozzle headers 290 being secured in a row 40 within the walls of the shoe so that the nozzles 91 projecting therefrom pass through the openings between the front wall 168 and the bottom wall 169 of the shoe.

For surface conditioning the side edge of the slab, an auxiliary blowpipe head 171 is provided. 45 The auxiliary head is similar in construction to the main head but shorter and comprises a shoe 172 having similarly arranged walls within which is a single nozzle header having nozzles 91 that pass through openings between the front and bottom walls of the shoe 172. The auxiliary shoe 172 is positioned so that its row of nozzles is vertical and is secured at one end of the main shoe 159 by suitable means such as screws 173 that secure the upper side wall of the shoe 172 to the 50 bottom end of the guide 160 and by a bracket 174 secured between the rear portion of the upper side wall of the shoe 172 and the rear portion of the right-end wall of the shoe 159.

Heating gas mixture is supplied to the nozzle 60 headers 290 by blowpipes 293 which are vertically disposed and braced by the crossbar 294 which has its ends secured to the guides 160. The blowpipe 293' for supplying heating gas mixture to the auxiliary head 171 is secured against the 65 rear wall 170 of the shoe 159 and its outlet is connected with the blowpipe header of head 171 by a conduit 175. The oxidizing gas is supplied to the nozzle headers by conduits 295 and 295', respectively, which have flexible portions connected to 70 manifolds within a housing 176 on the platform 177 formed by the upper portion of the cross member 153. Suitable flexible conduits 178 connect the gas inlets of the blowpipes 293 and 293' to corresponding manifolds within the housing 75 176.

The operation of the surface-conditioning apparatus shown in Figs. 10 to 14, inclusive, is similar to that previously described. When a slab S is moved into position for initiating the conditioning treatment, the motor 247 is operated in a 5 direction that causes the head H' to be lowered until the bottom 169 of the head H' is resting in contact with the upper surface of the slab. The heating gases are turned on and ignited and when the surface metal impinged thereby has reached 10 the ignition temperature the oxidizing gas is turned on and the slab S advanced through the machine. The head H' will ride in contact with the surface of the work during the operation, the auxiliary head 171 being maintained in contact 15 with the right-hand edge surface of the slab by the action of the horizontally swinging links 150 and the spring 154. The head H' will be free to tilt laterally in the vertical plane in order to follow a twist or warp of the slab surface and the auxiliary head 171 will be maintained constantly 20 in alignment with the edge surface. When the slab is turned over, the opposite edge surface will be in position for treatment simultaneously with the surface that was formerly on the bottom. 25

The invention is not limited to the exact details disclosed and it will be seen that certain features of the invention may be used independently of the others and changes may be made in various features of the apparatus without departing from 30 the essentials of the invention. For example, although the mechanisms herein described in detail are especially adapted for desurfacing steel slabs it is contemplated that the same principles are applicable to mechanism for removing scale from 35 the surfaces of slabs and other shapes. Furthermore, other types of blowpipes may be employed, for example; a blow-pipe providing a continuous sheet-like gas stream; or a row of blowpipe nozzles each having more than one oxidizing gas orifice; or a row of blowpipe nozzles each having a slot-like oxidizing gas orifice producing a row of 40 ribbon-like oxidizing gas streams which form, in effect, a continuous sheet-like stream; or blowpipes providing a single row of separate high- 45 temperature flames directed substantially perpendicularly against the work.

It is contemplated that at least one edge surface of a slab may be thermally conditioned by providing an additional blowpipe head disposed 50 at one end of the main blowpipe head and depending vertically downward therefrom for projecting gas simultaneously against the edge of the slab the added head being urged toward the edge surface to maintain it in operative relation 55 to such surface during the relative movement between the heads and the slab.

We claim:

1. Apparatus for thermo-chemically removing surface metal from a ferrous metal body such as a steel slab comprising a blowpipe head having nozzle means adapted to project a substantially sheet-like stream of oxidizing gas obliquely against a relatively wide area of a surface of said slab; a frame for supporting said head; means for supporting said slab in a position for surfacing treatment; means for effecting relative movement of said head with respect to said slab in a direction along said surface of and from one edge to the opposite edge of said slab; and mechanism for supporting said head on said frame constructed and arranged to maintain said nozzles in the operating position with respect to said surface by providing both limited perpendicular movement of said head in accordance with 60
2. Apparatus for thermo-chemically removing surface metal from a ferrous metal body such as a steel slab comprising a blowpipe head having nozzle means adapted to project a substantially sheet-like stream of oxidizing gas obliquely against a relatively wide area of a surface of said slab; a frame for supporting said head; means for supporting said slab in a position for surfacing treatment; means for effecting relative movement of said head with respect to said slab in a direction along said surface of and from one edge to the opposite edge of said slab; and mechanism for supporting said head on said frame constructed and arranged to maintain said nozzles in the operating position with respect to said surface by providing both limited perpendicular movement of said head in accordance with 65
3. Apparatus for thermo-chemically removing surface metal from a ferrous metal body such as a steel slab comprising a blowpipe head having nozzle means adapted to project a substantially sheet-like stream of oxidizing gas obliquely against a relatively wide area of a surface of said slab; a frame for supporting said head; means for supporting said slab in a position for surfacing treatment; means for effecting relative movement of said head with respect to said slab in a direction along said surface of and from one edge to the opposite edge of said slab; and mechanism for supporting said head on said frame constructed and arranged to maintain said nozzles in the operating position with respect to said surface by providing both limited perpendicular movement of said head in accordance with 70
4. Apparatus for thermo-chemically removing surface metal from a ferrous metal body such as a steel slab comprising a blowpipe head having nozzle means adapted to project a substantially sheet-like stream of oxidizing gas obliquely against a relatively wide area of a surface of said slab; a frame for supporting said head; means for supporting said slab in a position for surfacing treatment; means for effecting relative movement of said head with respect to said slab in a direction along said surface of and from one edge to the opposite edge of said slab; and mechanism for supporting said head on said frame constructed and arranged to maintain said nozzles in the operating position with respect to said surface by providing both limited perpendicular movement of said head in accordance with 75

changes in the level of said surface and also limited lateral canting of said head in response to any lateral twist or warp of the surface encountered during said relative movement.

5. 2. Apparatus for thermo-chemically removing surface metal from a ferrous metal body such as a steel slab comprising a blowpipe head having nozzle means adapted to project a substantially sheet-like stream of oxidizing gas obliquely against a relatively wide area of a surface of said slab; a frame for supporting said head; means for supporting said slab in a position for surfacing treatment; means for effecting relative movement of said head with respect to said slab in a direction along said surface of and from one edge to the opposite edge of said slab; and mechanism for supporting said head on said frame, said mechanism including means for counterbalancing a substantial portion of the weight of said head, and column means on said frame connected to each end of said head for supporting the same, said column means being constructed and arranged to co-operate with said head to permit free and independent vertical movement of either end of said head in accordance with the level of the adjacent edge of the surface.

3. Apparatus for thermo-chemically removing surface metal from a ferrous metal body such as a steel slab comprising a blowpipe head having nozzle means adapted to project a substantially sheet-like stream of oxidizing gas obliquely against a relatively wide area of a surface of said slab; a frame for supporting said head; means for supporting said slab in a position for treatment of said surface; means for effecting relative movement between said head and said slab in a direction lengthwise of said surface and from one end edge to the opposite end edge of said slab; and mechanism for supporting said head on said frame, said mechanism including column means on said frame connected to each end of said head for guiding the same, said column means being constructed and arranged to cooperate with said head to permit free and independent vertical movement of either end of said head in accordance with the level of the adjacent edge portion of said surface, a pair of devices cooperatively associated with said head and said column means and adapted to move said head toward and away from said surface, and common means for operating said devices simultaneously.

4. Apparatus for thermo-chemically removing surface metal from a ferrous metal body such as a steel slab comprising a blowpipe head having nozzle means adapted to project a substantially sheet-like stream of oxidizing gas obliquely against a relatively wide area of a surface of said slab; a frame for supporting said head; means for supporting said slab in a position for treatment of said surface; means for effecting relative movement between said head and said slab in a direction lengthwise of said surface and from one end edge to the opposite end edge of said slab; and mechanism for supporting said head on said frame, said mechanism including column means on said frame connected to each end of said head for guiding the same, said column means being constructed and arranged to cooperate with said head to permit free and independent vertical movement of either end of said head in accordance with the level of the adjacent edge portion of said surface, ways transversely disposed with respect to the length

dimension of said slab, and means for moving said frame along said ways for positioning said head transversely with respect to said surface.

5. In a machine for thermally conditioning the surface of a metal body such as a steel slab; a relatively wide blowpipe head adapted to project gas against the top surface of such body, the width of said head being sufficient to project gas on a narrow transverse zone of said surface extending completely across the surface; a supporting frame; means connected to said frame for vertically guiding each lateral end of said blowpipe head independently of the other; and means on said frame for lifting said head by engaging with and simultaneously raising both ends of said head.

6. A machine as claimed in claim 5 in which said guiding means is constructed and arranged to confine the movement of said head solely in a plane transversely of said body and normal to said surface.

7. A machine as claimed in claim 5 in which said guiding means is constructed and arranged to confine the movement of said head solely in a plane transversely of said body and normal to said surface, and for providing vertical movement of said head through a relatively large displacement and lateral rotation of said head in said plane between limits.

8. A machine as claimed in claim 5 which includes means for counterbalancing a substantial portion of the weight of said head.

9. A machine as claimed in claim 5 in which said lifting means is constructed and arranged to automatically disengage with said head when the head is lowered into contact with said surface.

10. A machine as claimed in claim 5 in which said frame is supported by a carriage for moving said frame and said head thereon horizontally with respect to said body.

11. A machine for thermally conditioning the surface of a metal body such as a steel slab according to claim 5 including a plurality of rollers secured to the lower portion of said head for engaging with the surface of said slab to maintain said head substantially parallel to said surface.

12. A machine according to claim 5 in which said lifting means are connected to said head by horizontally swingable links whereby said head is freely movable transversely for maintaining said head in alignment with an edge of the slab.

13. In a machine for thermally conditioning the surface of a metal body such as a steel slab; a relatively wide blowpipe head adapted to project gas against the top surface of such body, the width of said head being sufficient to project gas on a narrow transverse zone extending completely across the surface; a supporting frame; vertical guides depending from said frame adjacent both lateral ends of said head; a bracket secured to and extending from each lateral end of said head, said bracket having members engaging said vertical guides for confining the movement of said head in a vertical plane; a vertical jack screw parallel to said guides adjacent each end of said head and rotatably supported by said frame; a nut in threaded engagement with each of said jack screws for vertical movement therealong upon rotation thereof; means for preventing the rotation of each of said nuts when the screws are rotated; each of said brackets having a portion engageable by

- said nuts upon upward movement of the nuts and disengageable therefrom upon downward movement of the nuts after said head makes contact with the surface of said body; and means for simultaneously rotating said jack screws for raising both ends of said head simultaneously.
14. In a machine for thermally conditioning the surface of a metal body such as a steel slab; a blowpipe device comprising a transverse front member having an edge portion adapted to be positioned adjacent a surface of said slab; a plurality of nozzle headers detachably secured to said front member adjacent to each other in a row along said edge portion of said front member, each of said headers being provided with a row of nozzles and arranged so that the several rows of nozzles are aligned to form a continuous evenly spaced row of nozzle orifices extending along substantially the full width of said blowpipe device; and means for supplying oxidizing gas and fuel gas to said headers.
15. Apparatus according to claim 14 in which said transverse front member is provided with a chamber for cooling fluid and means is provided for passing cooling fluid therethrough.
16. Apparatus according to claim 14 including a wide multiple nozzle shoe having a bottom adapted to engage the surface of the work, said shoe having also a front wall and a row of openings extending from the inside to the outside of said shoe adjacent the corner between the front and bottom walls of the shoe, said nozzles severally extending from the inside of the shoe into said openings so that only the orifice ends of said nozzles are exposed.
17. Apparatus according to claim 14 including a wide multiple nozzle shoe having a bottom adapted to engage the surface of the work, said shoe having also a front wall and a row of openings extending from the inside to the outside of said shoe adjacent the corner between the front and bottom walls of the shoe, said nozzles severally extending from the inside of the shoe into said openings so that only the orifice ends of said nozzles are exposed and said front wall being secured to said front member independently of said nozzle headers.
18. Apparatus according to claim 14 including a wide multiple nozzle shoe having a bottom adapted to engage the surface of the work, said shoe having also a front wall and a row of openings extending from the inside to the outside of said shoe adjacent the corner between the front and bottom walls of the shoe, said nozzles severally extending from the inside of the shoe into said openings so that only the orifice ends of said nozzles are exposed; said shoe having also rear and end walls forming with the front and bottom walls, a chamber for cooling fluid, said front member being provided with a chamber for cooling fluid, and means for supplying cooling fluid to both chambers comprising an inlet to the chamber of said front plate, a connection from the chamber of said front plate to one end of the chamber of said shoe, and an outlet from the other end of the chamber of said shoe.
19. Apparatus according to claim 14 including a supporting frame; means for supporting said body in a position to be operated upon; means for effecting relative motion between said frame and said body longitudinally along a surface thereof; means on said frame for vertically guiding each end of said front member independently of the other and adapted to maintain said row of orifices parallel to said surface during such relative movement.
20. In a machine for thermally conditioning the surface of a metal body such as a steel slab; a relatively wide blowpipe head adapted to project gas against a horizontal surface of such body, the width of said head being sufficient to project the gas on a narrow transverse zone of said surface extending completely across the surface; a supporting frame for said head; means for supporting said body in a position to be operated upon; means for effecting relative motion between said frame and blowpipe head and said body longitudinally along said surface; means on said frame for moving said head away from and toward said surface; and other means connected to said frame for guiding each lateral end of said blowpipe head independently of the other arranged to confine the movement of said head in a plane substantially transverse to said body for providing movement of said head in a direction away from said surface through a relatively large displacement and lateral canting of said head between limits.
21. In a machine for thermally conditioning the surface of a metal body such as a steel slab; a relatively wide main blowpipe head adapted to project gas against the top surface of such body, the width of said head being sufficient to project gas on a narrow transverse zone extending completely across said top surface; an auxiliary blowpipe head disposed at one end of said main blowpipe head and arranged at an angle thereto for projecting gas on a narrow zone across an edge surface adjacent to said top surface; a supporting frame; column means on said frame disposed adjacent each end of said main head; and supporting mechanism connecting said main head and said auxiliary head to said column means, said mechanism being constructed and arranged for providing free and universal movement of said heads in a plane transverse to said slab for maintaining said main head in uniform alignment across the top surface of the slab and said auxiliary head in uniform relation to the edge surface of the slab irrespective of a twist or warp in the slab and departure from straightness of the edge surface.
22. Apparatus according to claim 21 in which said mechanism comprises a transverse member; horizontally swingable links connecting each end of said transverse member to said column means; and means for adjustably supporting said main head on said transverse member arranged to provide a limited degree of free movement of said head toward and away from the top surface and lateral canting of said head between limits.
23. Apparatus according to claim 21 in which said mechanism comprises a transverse member; a bracket member slidably movable vertically along each of said columns; means engaging said bracket members for raising and lowering said bracket members simultaneously; horizontally swingable links pivotally connecting each end of said transverse member to a respective bracket member; and means for adjustably supporting said main head on said transverse member arranged to provide a limited degree of free movement of said head toward and away from the top surface and lateral canting of said head between limits.
24. Apparatus for thermo-chemically removing surface metal from a ferrous metal body such as a steel slab comprising a blowpipe head

having nozzle means adapted to project a substantially sheet-like stream of oxidizing gas obliquely against a relatively wide area of a surface of said slab; a frame for supporting said head; means for supporting said slab in a position for treatment of said surface; means for effecting relative movement between said head and said slab in a direction lengthwise of said surface and from one end edge to the opposite end edge of said slab; and mechanism for supporting said head on said frame, said mechanism including column means on said frame connected to each end of said head for guiding the same, said column means being constructed and arranged to cooperate with said head to permit free and independent vertical movement of either end of said head in accordance with the level of 5 the adjacent edge portion of said surface, and means on said frame adapted to move said head toward and away from said surface.
